UNITED STATES PATENT OFFICE.

JOHN HENRY SMITH, OF ZURICH, SWITZERLAND.

MANUFACTURE OF FILMS FOR PHOTOGRAPHIC PURPOSES.

No. 923,589.

Specification of Letters Patent.

Patented June 1, 1909.

Original application filed May 15, 1905, Serial No. 260,436. Divided and this application filed July 16, 1906.
Serial No. 326,448.

To all whom it may concern:

Be it known that I, JOHN HENRY SMITH, a subject of the King of Great Britain, residing in Zurich, in the Canton of Zurich, Republic of Switzerland, (whose post-office address is No. 417 Seestrasse, Zurich, Switzerland,) have invented certain new and useful Improvements in the Manufacture of Films for Photographic Purposes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present application is a division of my co-pending application filed May 15, 1905, Serial No. 260436.

20 The subject of the present invention is an improved process for the manufacture of sensitive photographic films, and in the drawing: Figure 1 shows a vertical section of a film, on an enlarged scale, constructed 25 according to my invention. Fig. 2 is a similar view showing a modification. Fig. 3 is a view similar to Fig. 1 showing still another modification.

My process consists in coating upon an appropriate smooth support a gelatin solution and after drying coating upon this again a solution of nitrocellulose. A sensitive photographic emulsion is coated upon the dried nitrocellulose surface and after the emulsion 30 is dried, the triple film is stripped from its support. A second film is prepared in the same manner omitting however the coating of the sensitive emulsion and this is also stripped from its support. The plain gelatin surfaces of the two component films are 35 then brought into contact and squeegeed together in a moist condition yielding the finished compound film shown in Fig. 1 in which *a*, *a'*, are the layers of gelatin, *b*, *b'*, the layers of collodion and *c* the layer of sensitive photographic emulsion.

Instead of making two separate films, one only need to be made and the half of the film only coated with the sensitive emulsion, 50 then the whole film stripped from its sup-

port, doubled up with the plain gelatin surface inside and squeegeed together to form the compound film seen in Fig. 2. Or again the compound film may be formed by either of the above methods but without the intermediate coating of the sensitive emulsion and the emulsion then coated upon the finished compound film after stripping.

In order that the emulsion should adhere tenaciously to the nitro-cellulose surface a substratum consisting of a solution of gum arabic or other suitable binding agent may be applied before the emulsion is coated.

Camphor, resins, balsams, oils, paraffins etc. may be added to the nitrocellulose solutions to increase the pliability or render the inner gelatin layer more impermeable by the photographic baths etc. or to render the process more economical.

Instead of squeegeeing two component 70 films together one only may be taken and the back or plain gelatin surface coated with a nitrocellulose solution after stripping, either before or after the sensitive emulsion has been coated (see Fig. 3). 75

What I claim is:—

1. The herein-described process for manufacturing a sensitive photographic film consisting in squeegeeing together into intimate contact two layers of gelatin which have 80 been previously coated with a protecting layer of nitrocellulose solution and coating one of the layers of nitrocellulose solution with a sensitive photographic emulsion.

2. The herein-described process for manufacturing a sensitive photographic film consisting in coating a gelatin layer with a nitrocellulose solution, coating the nitrocellulose solution with a sensitive photographic emulsion, stripping the whole from its support and coating the plain gelatin surface with a nitrocellulose solution. 90

In testimony whereof, I have signed my name to this specification in the presence of two subscribing witnesses.

JOHN HENRY SMITH.
